PLASTIC BATH TUB PROTECTOR UNIT
OR THE LIKE

Abraham Yormack, 32—60 Harvest Road, Wantagh, N.Y.

Filed July 28, 1965, Ser. No. 86,328

Term of patent 14 years

(Cl. D4—4)

FIG. 1.

FIG. 2.

FIG. 3.

FIG. 4

FIG. 5

FIG. 1 is a top plan view of a plastic bath tub protector unit or the like, showing my new design;

FIG. 2 is a side elevational view;

FIG. 3 is an elevational view;

FIG. 4 is a fragmentary cross-sectional view taken along line 4—4 of FIG. 2; and

FIG. 5 is a fragmentary cross-sectional view taken along line 5—5 of FIG. 1.

I claim:

The ornamental design for a plastic bath tub protector unit or the like, as shown.
